COIN CHANGER

Arnold R. Buchholz, Watertown, Wis., assignor
to Brandt Automatic Cashier Company, Water-
town, Wis., a corporation of Wisconsin

Application January 27, 1950, Serial No. 140,832

7 Claims. (Cl. 133-2)

1

The invention relates to coin changers.

As usually constructed coin changers operate on a dollar basis, that is, on the tender of one dollar the appropriate change of from one to ninety-nine cents will be delivered. In some instances special keys provide for returning change from a tender of fifty cents, seventy-five cents, or twenty-five cents. One object of the present invention is to provide mechanism having a shift bar for any tender that may be offered under a dollar by which the proper change due the purchaser is returned.

A further and important object of the invention is to provide a coin changer having mechanism for making change for any tender less than a dollar in which there is only one nickel compartment or stack having one ejector which does what would ordinarily be the work of three nickel compartments with their ejectors, thus keeping the width or size of the machine down to the limits used on the usual dollar tender machines.

The invention further consists in the several features hereinafter set forth and more particularly defined by claims at the conclusion hereof.

In the drawings:

Fig. 1 is a plan view of a coin changer embodying the invention;

Fig. 2 is a vertical sectional view taken on the broken line 2-2 of Fig. 1;

Fig. 3 is a horizontal sectional view taken along the line 3-3 of Fig. 2;

Fig. 4 is a vertical sectional view taken on the broken line 4-4 of Fig. 2;

Fig. 5 is a detailed vertical sectional view taken on the line 5-5 of Fig. 3;

Fig. 6 is a detailed vertical sectional view taken on the line 6-6 of Fig. 3;

Fig. 7 is a detailed vertical sectional view taken on the line 7-7 of Fig. 3;

Fig. 8 is a detailed vertical sectional view taken on the line 8-8 of Fig. 5;

Fig. 9 is an exploded view of the shift bar mechanism;

Fig. 10 is a side elevation view of a modified form of coin changer, parts being broken away and parts being shown in section;

Fig. 11 is a horizontal sectional view taken along the line 11-11 of Fig. 10;

Fig. 12 is a vertical sectional view taken on the line 12-12 of Fig. 10;

Fig. 13 is a detailed horizontal sectional view taken on the line 13-13 of Fig. 12;

Fig. 14 is a vertical sectional view taken on the line 14-14 of Fig. 10;

2

Fig. 15 is a prospective view of the nickel ejector control mechanism.

Referring to Figs. 1 to 9, the machine includes a metal housing having a base 18, sides 19, and back 20. A coin tray 21 is suitably removably mounted at the front end of the housing and is formed to provide coin compartments or chutes for the various denominations of coins. The chutes A, B, and C carry pennies in stacks, the chute D carries nickels, the chutes E and F, dimes, the chute G quarters, and the chute H half dollars. The ejector mechanism for the chute A is adapted to eject one penny at a time therefrom, and the ejector mechanisms for the chutes B and C are adapted to eject two pennies each at a time, so that either one penny, two pennies, three pennies, or four pennies can be dispensed from the machine as needed for change. The ejector mechanism for the chutes E and F are each adapted to eject one dime at a time while the ejectors for chutes D, G, and H are adapted to eject one coin at a time from each of said chutes.

A keyboard 22 is mounted on the top of the housing in back of the tray and carries change keys 23 numbered from 1 to 99 and special change keys 24 for 10, 25, 50 cents and one dollar and a lock release key 25. The keys 23 are similar to those of the prior U. S. Patent No. 1,850,198, of March 22, 1932, to Edward J. Brandt, and are mounted to slide in the keyboard, being pushed downwardly by the operator against the action of a return spring 26 some of which are shown, and each key having a rocker or rockers actuating finger 27 formed integral therewith or secured thereto and engageable with one or more rockers 28 having arms 29 pivotally mounted on pivots 30 mounted in the sides of the frame. Each rocker 28 carries an arm 31, some of which are shown in Fig. 2, pivotally connected by a pin 32 to the outer end of a suitably guided pusher bar or ejector operating member 33 or the members 33r, 330, or 335 hereinafter referred to. Each of the pusher bars is pivotally or thrust connected at its outer end to an ejector carrying slide or plate 34 which is slotted at 35 and 36 to receive guide rollers 37 and 38 carried by frame uprights 39 and 40, said plates 34 being similar to the plates 23 of the aforementioned patent. The ejectors each include a coin ejector finger 41 pivotally connected to its slide 34 by a pin 42 and having a second finger 43 pivotally connected to it intermediate its ends by a pin 44 which fingers are yieldingly urged apart by a spring 45 interposed between them and mounted

on a guide bolt 46. The slides 34 with their pusher bars 33 are spring returned in known manner to bring the ejector fingers to an inoperative position, the slide 34 for the nickel ejector, however, having a return spring 34a.

The above construction operates in known manner. The depression of any one of the keys 23 acting through the rockers 28, and pusher bars 33 and slides 34 move the fingers 41 and 43 through the lower slot 47 in the coin tray to eject one or more coins from the coin chutes. As in the aforementioned patent a coin engaging finger or lever 48 is pivotally mounted at its upper end 49 to work in an upper slot 50 in each chute of the tray. Each finger 48 is yieldingly held against the stack of coins by a bell crank locking lever 51 pivotally mounted on a transversely extending shaft 52 and urged by the greater weight of its roller carrying end 53 into engagement with said finger. During each reciprocation of its associated slide 34 the roller 53 rides on the top of a stop projection 54 on said slide when the finger 48 is in the position shown in Fig. 2. When, however, the coins C in the coin chute becomes depleted to three or less, then the finger 48 is free to swing outwardly, and the roller end 53 of the lever 51 drops downwardly into the path of movement of the stop projection 54 and thus prevents movement of the slide 34 and its ejector fingers to eject a coin.

The operation of the parts of the machine thus far described is the same as that of the aforementioned patent for delivering change of any amount from 1 to 99 cents on receipt of a tender of one dollar by the operation of the proper key 23 whose numbers represent the amount of the purchase price. For example, if a dollar is given for a one cent purchase, depression of the key 23 numbered 1 will through its finger 27 actuate the rockers 28, bars 33 to simultaneously move the slides 34 carrying the ejector fingers for the chutes H, G, F, E, C, and B to deliver 50¢, 25¢, 10¢, 10¢, 2¢, and 2¢ respectively, or 99¢ change. The special change keys 24 each have fingers to operate the ejectors which will deliver the amounts appearing on these fingers in the form of loose change in the same amount as received. The lock release key 25 is adapted in known manner to operate a swingable lock release bar 55 pivoted at 55a at the sides of the housing and movable upwardly to engage the locking levers 51 to move them out of the path of their slides 34 so as to permit dispensing one or more of the last three coins in a tray whose coins have become depleted to the extent that the finger 48 has swung outwardly into the tray.

As in said prior patent special keys 56 and 57 are provided to take care of tenders of 50¢ for the key 56 and either 25¢ or 75¢ for the key 57. These keys act as ejector cut-out or incapacitating keys and are shown in Fig. 4 slidably mounted in a plate 58 and normally urged upwardly by springs 59. The key 56 has a shank 60 carrying a pin 61 adapted to engage a projection 62 on a U-shaped frame 63 whose legs are pivoted at 64. Depression of key 56 causes pin 61 to swing frame 63 downwardly and thus depress the ejector finger 41 for the 50¢ piece stack downwardly so as to prevent feed of coins therefrom when a tender of fifty cents is received. This frame has cut outs 66, 67, and 68 to clear the ejector fingers for the chutes G, F, and E (25¢, 10¢, and 10¢), respectively. The key 57 has a shank 69 carrying a pin 70 adapted to engage a projection 71 on a U-shaped frame 72 whose legs are also

pivoted at 64. The projection 71 extends over the frame 63, so that depression of the key 57 causes pin 70 to swing frame 72 downwardly and with it the frame 63 and thus depress the ejector fingers 41 for the 50¢ stack and 25¢ stack downwardly so as to prevent feed of coins therefrom when a tender of either twenty-five cents or seventy-five cents is received. The frame 72 has cut-outs 73 and 74 to clear the ejector fingers for the chutes E and F for the dimes.

With this construction when a tender of fifty cents for a purchase less than fifty cents is received, the operator presses down the key 56 to prevent ejection of a coin from that chute taking place when she depresses one of the regular keys representing the amount of the purchase to deliver the change to the purchaser. Similarly, when tenders of 75¢ or 25¢ are received for purchases less than either of these amounts, the key 57 is depressed so as to prevent ejection of coins from either the 50¢ or the 25¢ chutes.

The present invention includes the above keys 57 and 56 and keys 75 and 76 which take care of operating the machine to give change for any tender less than a dollar of an amount ending in five or zero, that is, five cents or ten cents, or any multiple of these not including 25, 50, and 75 cents. The key 75 numeralled 5 is slidably mounted in the plate 58 and urged upwardly by a spring 77, and the key 76 is similarly mounted. The shanks 78 of each of these keys carry pins 79 adapted to engage one of the projections 80 of a third U-shaped frame 81 pivoted at 64, the projections 80 extending over the frames 63 and 72 so that depression of either key 75 or 76 acts to depress all the frames 63, 72, and 81.

During any one change making operation each of the keys 56, 57, 75, and 76 is temporarily locked when depressed by engagement of a swinging latch member 82 with a downwardly tapered projection 83 on each key, the member 82 being U-shaped and pivotally mounted at its ends 82a on a bracket 84 secured to the base of the machine and yieldingly urged to a locking position by a spring 85. After each operation any one of the locked keys 56, 57, 75, and 76 is released by means that move the latch 82 to a release position against the action of its spring 85 comprising cam projections 86 engaged by a U-shaped lock release bar 87 pivotally mounted in the sides of the machine and adapted to be engaged by the front end 88 of any one of the slides 34 and be swung thereby into engagement with said projections 86 so as to swing the latch 82 clockwise as viewed in Fig. 2 to release it from any of the locked special keys as the slide 34 completes its ejection movement when its controlling change key is depressed.

In order to make change on a basis of a tender of any amount less than a dollar the keys must be capable of moving the nickel ejector for any amount tendered to and including ninety-five cents. Because of this the usual operation of the nickel ejector for a dollar tender is not sufficient, but the nickel ejector must be capable of operation when any of the regular keys from 1 to 95, inclusive, are depressed though in some instances the nickel ejector is not actually operated. To render the nickel ejector effective for operation from the keys 1 to 95 each of these keys has a finger which when the key is depressed will either act upon the ordinary nickel rocker or supplemental rockers. Referring to Figs. 2 and 3, the rocker 28r for operating the nickel

ejector on a dollar basis is connected to the pusher bar 337. In addition a rocker 280 for operating the nickel ejector, on a tender of less than one dollar of ten cents or a multiple thereof excluding fifty cents, is connected to a pusher bar 330 and a rocker 285 for operating the nickel ejector, on a tender of less than a dollar of five cents or a multiple of five excluding twenty-five and seventy-five cents is connected to a pusher bar 335. Each of the pusher bars 337, 330, and 335 is adapted to be brought into and out of operative position with a pin 89 on the slide 34 for the ejectors associated with the nickel compartment shown in Fig. 2, each bar having a notched pin engaging end 99 which in the raised position of the bar engages said pin and in the lowered position of the bar clears said pin. Since in connection with tenders less than one dollar the ordinary or regular pusher 337 cannot be used, this bar is dropped down when either of the pusher bars 330 or 335 is to be operated, and as a consequence the means for raising and lowering the pusher bars 337, 330, and 335 are controlled by mechanism associated with the special keys 75 and 76 which are the 5 and 0 special keys on the keyboard.

Referring to Figs. 2 to 7, the key 75 is provided with a wedge, a cam projection 91 similar to the projection 94 on the key 76 which on the depression of the key engages a roller 92 on a push bar 93 to move said bar inwardly as viewed in Fig. 3. The key 76 is similarly provided with a cam projection 94 which on the depression of the key engages a roller 94a, on a push bar 95 to move said bar inwardly. A pivot shaft 96 is mounted on fixed uprights 96a, and a second shaft 97 is pivotally mounted in said uprights and forms a part of swinging frame 98 which has spaced arms 99 and 100 and an arm 101. A raising and lowering lever or finger 102 for the bar 337 is pivotally mounted on the shaft 96 and has a pin and slot connection 102a with the arm 101. A U-shaped frame member 103 is pivotally mounted on the shaft 96 and has a finger projection 104 for raising and lowering the bar 330 and an arm 105 which extends up between the rear end 95a of the push bar 95 and the arm 99 of the frame 98. A U-shaped frame member 106 is also pivotally mounted on the shaft 96 and has a finger projection 107 for raising and lowering the bar 335 and an arm 108 which extends up between the rear end 93a of the push bar 93 and the arm 100 of the frame 98. The frames 98, 103, and 106 are each biased to a position in which the finger 102 is in a raised position and the fingers 104 and 107 are in a lowered position by tension springs 109, 110, and 111, respectively, connected to said frames and to the housing, and Figs. 5 and 8 show the regular pusher bar 337 engaged with the pin 89 for operation of the machine on a dollar tender basis. If now the tender is less than a dollar in any amount except 50¢ ending in zero, the operator presses down on the 0 key or key 76, and this we have seen depresses all three of the frames 63, 72, and 81, thus cutting out the ejectors for 50¢, 25¢, 10¢, and 10¢ and at the same time moving the push bar 95 inwardly causing it to engage the arm 105 and by it swing the frame 103 counterclockwise and thus swing finger 104 so as to raise the bar 330 to bring its notched bifurcated end 330a into engagement with the pin 89. At the same time since the arm 105 abuts the arm 99, the frame 98 swings or turns with its pivot shaft 97 in the same di-

rection and swings arm 101 upwardly which through the pin and slot connection 102a causes the lever 102 to swing down so that bar 337 is lowered to an inoperative position while the bar 330 becomes effective to operate the slide 34 for the nickel ejector. If the tender is less than a dollar in any amount except 25¢ and 75¢ ending in five, the operator presses down on the 5 key or key 75, and this similarly depresses all three of the frames 63, 72, and 81, thus cutting out the ejectors for 50¢, 25¢, 10¢, and 10¢ and at the same time moving the push bar 93 inwardly causing it to engage the arm 108 and by it swing the frame 106 counterclockwise and thus swing the finger 107 upwardly so as to raise the bar 335 to bring its notched end 335a into engagement with the pin 89. Since the arm 100 abuts the arm 108, under these conditions the frame 98 swings with the frame 106 causing the arm 101 to swing the finger 102 down in the same way as described in connection with the push bar 95. Thus the slide 34 for the nickel ejector has three push bars 337, 330, and 335 selectively available for operating it so that if the rocker associated with the push bar is then in an operative position relative to the slide, the slide will be operated to eject a nickel from the nickel stack.

As examples of the method of operation of the above described structure, assume the purchase price of an article to be 65¢. When the purchaser tenders a dollar for this article, it is only necessary for the operator to press downwardly on the 65 key, and this will act through its fingers to move the ejectors for the chutes F and G to eject a 10¢ piece and 25¢ piece, respectively. If now the tender for this 65¢ article is 75¢, then the operator first presses down on the special key 57 numeralled 25, 75 in Fig. 1 of the drawings. This operation incapacitates the ejectors for the chutes H and G and the ejector for the chute E is operative as before to eject 10¢. If the tender is 70¢, which is a number ending in zero or one of the multiples of ten, the operator first presses down on the key 76 which is the zero key, thus incapacitating the ejectors for the chutes H, F, G and E and at the same time in doing this operates the pusher bar 95 which as previously explained acts through the frame 98 to move the finger 102 down so that the connection from the regular nickel push bar is shifted to the 330 push bar and then on pushing down the 65 button, the ejector for the chute D is operated and 5¢ in change is delivered.

The key 65 for the dollar tender does not have any element 27 to operate the rocker 287, but it does have an element 27 to operate the rocker 280 so that the depression of the special key 76 puts the machine in a condition where the depression of key 65 can operate the nickel ejector bar push bar 330. It is also to be noted that some of the keys are provided with one or more elements 27 to selectively cooperate with the rockers 287, 280 and 285.

Assuming the purchase price to be 32¢ and the tender a dollar, pressing down on the 32 key operates the ejectors for the penny chute A, the two penny chute C, the nickel chute D, the first 10¢ chute E, and the 50¢ chute H whereby 68¢ in change is delivered to the purchaser. Now if the tender is 50¢ for this purchase, the operator first presses down on the key 56, thus incapacitating the 50¢ ejector and then on depressing the 32 key the ejectors for the chutes A, C, D, and E, one penny, two penny, 5¢, and 10¢, respectively,

are operated dispensing the 18¢ change. In each of these two transactions the nickel ejector operates in the normal manner. If for the 32¢ purchase, 40¢ is tendered, then the zero key 76 is first depressed incapacitating the ejectors of the chutes E, F, G, and H, and at the same time shifting the drive from the pusher bar 33r to the pusher bar 330, and then when the 32 key is depressed since the key 32 also has a finger 27 which will operate the bar 330, the ejectors for the chutes A, C, and D will be operated to eject 8¢ change. If for this same purchase price the amount tendered is 35¢, then the key 75 or the 5 key is depressed which incapacitates the chutes E, F, G, and H and at the same time acts on the pusher bar 93 to shift the drive from the pusher bar 33r to the pusher bar 335, and then when the key 32 is depressed, the ejectors for the 1¢ chute A and the two penny chute C are operated to deliver three cents and the operation of the push bar 93 in shifting the drive from the bar 33r to the bar 335 has rendered the regular nickel ejector ineffective, also the rocker 285 which operates the bar 335 is then not actuated since there is no finger 27 on the key 32 for operating rocker 285.

The machine shown in Figs. 10 to 15 is similar to the first described form except that the coin tray 21 is arranged at the back of the machine and the keyboard 22 is in front of it, and the special keys are adjacent the front side of the machine. This arrangement involves certain changes in some of the parts previously described. Similar parts have been similarly designated.

Referring to Fig. 10, the change keys 23 with their rocker actuating fingers 27 engage the rockers 28 which have arms 29 pivotally mounted on pivots 30 mounted in the sides of the frame of the machine carry arms 31 pivotally connected by pins 32 to pusher bars 33. Each pusher bar is pivotally connected by a pin 33a to an ejector lever 112 pivotally mounted on a transversely extending shaft 113 and having an ejector finger 114 pivotally mounted thereon at 115 which ejector works through the slot 47 of the coin tray and is yieldingly urged upwardly by a spring 116. Only the ejector for the nickel tray is shown in full in side elevation, but the other ejector levers 112 and their pusher bars 33 are shown in Fig. 11. Each lever 112 is urged to a retracted position by a spring 117.

The coin depletion lever 48 and its associated bell crank lever 51 are shown in Fig. 10 and act in the same way to stop the operation of the machine. Normally a roller 118 on the upper end of the lever 112 passes under the lever 51, but when on coin depletion the lever 48 swings out into the coin chute or compartment, the outer end of the lever 51 swings downwardly into the path of movement of the lever 112 and strikes said lever on its forward movement, thus preventing further delivery of coins. A lock release key operated bar similar to the bar 55 may be associated with the lever 51 in this form, if desired.

Referring to Fig. 14, the keys 119, 120, 121, and 122 correspond to the keys 75, 57, 56, and 76 previously described and are slidably mounted in a top portion 123 of the machine, and in each instance returned to inoperative position by a spring 124.

Referring to Fig. 10, a bracket 125 mounted on the base of the machine and provided with arms 125a has the lower ends of the shanks of keys 119 to 122 slidably mounted therein and car-

ries a pivot shaft 126 on which levers 119a, 120a, 121a, and 122a are pivotally mounted, each of said levers having a cam surface 127 adapted to be engaged by the lower end of the associated key so that when said key is depressed, this lever will be rocked clockwise as viewed in Fig. 10. The shanks of the keys 119 and 122 are each bifurcated and each bifurcation acts on its associated lever so that there are two levers 119a for the key 119 and two levers 122a for the key 122. With the exception of one of the levers 122a, each of the levers 119a to 122a is pivotally connected at 128 to a pull bar or link. In Fig. 11 these links are designated 119b, 119c, 120b, 121b, and 122b. The inner lever 122a is directly connected to the inner lever 119a by a tie bar 122c.

Referring to Fig. 12, the ejector fingers 114 (starting from the left) are for the fifty cent coin stack, the twenty-five cent stack, and the two dime stacks, respectively, and a throw out member 129 is associated with the fifty cent ejector finger, a throw out member 130 is associated with the twenty-five cent finger, and a throw out member 131 is associated with the two ten cent ejector fingers. The member 131 is shown in side elevation in Fig. 10. A bell crank lever is operatively connected to each of the throw out members and its operating link, and each of these levers is pivotally mounted on hollow spacer sleeves 132 mounted on the pivot shaft 113 for the ejector levers 112. The throw out member 129 is guided at its top by a pin 133 working in a slot thereof and is pivotally connected at its lower end by a pin 134 to an upstanding ear on one arm 135 of the bell crank lever 136 whose other arm is pivotally connected by a pin 137 to the end of the pull bar 121b. Thus movement of bar or link 121b by depressing the 50¢ key 121 will move the member 129 downwardly and with it the ejector finger to incapacitate it. The throw out member 130 is guided at its top in the same way as the member 129 and is pivotally connected at its lower end by a pin 138 to an upstanding ear on one arm 139 of the bell crank lever 140 whose other arm is pivotally connected by a pin 141 to the end of the pull bar 120b. As this pull bar is operated by the 25¢, 75¢ key the arm 139 has a projection 139a that extends over the arm 135 so that depression of the key 121 will through movement of the bar 120b by the lever 120a swing the lever 140 so as to pull down on the member 130 and also by engagement of the arm 139a with the arm 135 move the lever 136 so as to pull down on the member 129 so that both 50¢ and 25¢ ejectors are rendered inoperative. The throw out member 131 is guided like the others above described and is pivotally connected at its lower end by pin 142 to an upstanding ear on one arm 143 of the bell crank lever 144 whose other arm is pivotally connected by a pin 145 to the end of the pull bar or link 119c which due to the tie bar 122c may be operated by depressing either the key 119 or the key 122. The arm 143 of the bell crank 144 has a projection 143a that extends over the arm 139 with the result that when either the key 119 or 122 is depressed, the pull bar or link 119c acting on the lever 144 pulls down on the throw out member 131 to render the two dime ejectors inoperative and at the same time since projections 143a and 139a connect the bell cranks 144 and 139 for movement with the bell crank 144, the members 131 and 129 are also pulled down to throw out the quarter and fifty cent ejectors. It will be noted from the above that this arrangement performs the same function as

the key controlled frames 63, 72, and 81 of the first described construction.

As in the first construction, the nickel ejector is adapted to be operated by either one of three separate key-controlled rockers whose connections with the nickel ejector lever are controlled by the operations of the keys 119 and 122 and their pull bars or links 119b and 122b. A push bar 33rm connected to the rocker 28r has a forked end engageable with a pin 146 on the ejector lever 112 for the nickel compartment. The rocker 280 is pivotally connected to one end of the push bar 330m whose forked end 147 may engage the pin 146. The rocker 235 is pivotally connected to one end of the push bar 335m whose forked end 148 may engage the pin 146. For selectively controlling the positioning of the push bars 33rm, 330m, and 335m by the keys 119 and 122 which correspond to the 5 key and zero key of the first construction the mechanism best shown in Fig. 15 is used. This mechanism includes a base frame 148 having upstanding ears 150 for a pivot shaft 151 and having upstanding ears 152 for a pivot shaft 153. The shaft 151 has U-shaped frames 154 and 155 pivotally mounted thereon, both of which are normally moved to the position shown in Fig. 15 by a spring 156 acting on a lever 157 which carries a pin 158 that engages one of the arms of each frame 154, 155. The other arm of the frame 154 is pivotally connected at 159 with the pull bar or link 119b. The other arm of the frame 155 is pivotally connected at 160 with the pull bar or link 122b. An elevating finger 161 for the bar 330m forms one arm of a bell crank lever 162 pivoted on the shaft 153 and operatively connected by a link 163 with one arm of the frame 154. An elevating finger 164 for the bar 335m forms one arm of bell crank lever 165 pivoted on the shaft 153 and operatively connected by a link 166 with one arm of the frame 155. An elevating finger 167 for the bar 33rm forms one arm of a plain lever 168 pivoted on the shaft 153 and operatively connected at 169 to one arm of the lever 157 which is a bell crank lever. From Fig. 15 it will be noted that the arrangement of these levers is such that when the finger 167 is up so that the regular nickel pusher 33rm is operating, the fingers 161 and 164 are down and the push bars 330m and 335m are in inoperative position. When, however, the frame 154 is tilted counterclockwise by the depression of the key 119 acting through the link 119b, the finger 161 is raised while simultaneously the lever 157 turns to swing the lever 168 clockwise and depress the finger 167. Similarly, when the frame 155 is tilted counterclockwise by the depression of the key 122 acting through the link 122b, the finger 164 is raised while simultaneously the lever 157 turns to swing the lever 168 clockwise and depress the finger 167. Thus the selective keys 119 and 122 act to control which of the pusher bars are positioned to actuate the nickel ejector lever.

As in the first described construction the keys 119, 120, 121, and 122 are adapted to be locked in by the engagement of a latch member 170, similar to the member 82, pivoted at 171 and normally urged to a locking position by a spring 172, each of the keys having one or more projections 173 engageable with said latch. After each paying operation under the control of any one or more of the keys above mentioned, the latch is released on the return of any one of the operated change keys 23 by a connection of a change key operated U-shaped release bar 174 pivoted

on the base of the machine and shown in Fig. 11 as projecting over the free end of a release lever 176 pivoted at 177 on one of the arms 125a and having a latch throw out cam surface 178 engageable with an arm of the latch 170 to shift said latch out of locking position when said free end of the lever 176 is tilted downwardly by the depression of the bar 174 by any of the rockers 28 for any of the change keys 23. The lever 176 is returned by a spring 179.

The method of operation of the modified form is the same as the first form. The modified form is preferred because the ejector operating means is simpler and the coin tray is above the keyboard. In this connection, the coins are ejected by the ejectors into a trough 183 which has a side outlet 181.

In each instance while two additional rockers for operating the nickel ejector mechanism have been added to the changer of the patent previously referred to, this does not act to increase the length of the machine and its width stays the same since the one nickel tray with the ejector link shifting mechanism above described takes care of what would ordinarily be taken care of by three separate ejectors and trays.

It will be noted that by the hold down mechanism controlled by the keys 75, 53, 56, and 76 in the first form and 119, 120, 121, and 122 in the second form any key in the keyboard will deliver change from every possible tender, these keys acting as previously noted to render one or more of the ejectors inoperative.

I desire it to be understood that this invention is not to be limited to any particular form or arrangement of parts except in so far as such limitations are included in the claims.

What I claim as my invention is:

1. In a coin changing machine, the combination of a keyboard having a plurality of sales keys numbered from 1 to 99, a coin tray having compartments for pennies, nickels, dimes, quarters, and half dollars, a reciprocatory ejector mechanism for each of said compartments including an ejector finger capable of movement to an inoperative position, a change key operated rocker and pusher for each of said ejector mechanisms by which change from said compartments can be effected on a dollar tender basis, additional rockers and pushers for the ejector mechanism for the nickel compartment for operating on tenders of less than a dollar in connection with the operation of the change keys from 1 to 95, and additional key controlled mechanism for selecting which of said additional rockers and pushers for the nickel ejector mechanism shall be effective on the operation of any particular change key when making change for tenders less than one dollar.

2. The structure as defined in claim 1 wherein the reciprocatory ejector mechanism comprises a pivoted lever mounted at the rear of the machine and having its coin ejector finger pivotally mounted thereon and the keys for controlling the additional key controlled mechanisms for the selective additional rockers and pushers for the nickel ejector mechanism are disposed at the front of the machine.

3. In a coin changing machine, the combination of a keyboard having a plurality of sales keys numbered from 1 to 99, a coin tray having compartments for pennies, nickels, dimes, quarters and half dollars, ejector mechanism for each compartment comprising a lever pivotally mounted on the machine at the rear thereof and a coin

ejector finger operatively connected with said lever, a change key operated rocker and pusher operatively connected to each of said levers for moving said levers and fingers to make change from said compartment on a dollar tender basis, additional selectively operable rockers and pushers for operating the ejector lever for the nickel compartment when making change on tenders of less than a dollar on operating the change keys from 1 to 95, and separate key controlled mechanisms for selecting which of said selectively operable rockers and pushers shall be operative to operate the said ejector lever for the nickel compartment on a less than a dollar tender basis when operating the change keys from 1 to 95 and for simultaneously incapacitating the rocker and pusher for operating the nickel ejector on a dollar basis.

4. The structure as defined in claim 3 wherein the separate key controlled mechanisms are levers engageable with cooperative pushers to move them to nickel ejector lever operating position.

5. In a coin changing machine, the combination with a coin tray having compartments for pennies, nickels, dimes, quarters and half dollars, change keys from 1 to 99, change key controlled ejector mechanisms for said compartments by which change from said compartments can be effected on a dollar tender basis, said ejector mechanisms having coin ejector fingers capable of movement to an inoperative position, key-controlled means for moving the fingers of certain of said ejector mechanisms to an inoperative position when operating said change keys on a tender of twenty-five, fifty, or seventy-five cents, additional key controlled means for effecting the operating of said first named finger moving means and also for moving the fingers of other of said ejector mechanisms to an inoperative position when operating said change keys on a tender of five cents or a multiple thereof or tens or multiple thereof, latching means for retaining said ejector finger moving means in an operative position until a change key has been operated, means for releasing said latching means at the completion of the operation of any one of the change keys, there being a single nickel ejector mechanism and a plurality of means for operating said nickel ejector mechanism by any of said change keys 1 to 95, and means operated by said additional key controlled means for selecting which of said nickel ejector mechanism operating means is effective to operate said nickel ejector on the operation of any particular change key for making change including a nickel.

6. In a money handling machine adapted to be operated to liberate different combinations of coins, the combination of means for normally operating the machine on a dollar tender basis including change keys 1 to 99 representing purchase amounts and coin dispensing mechanism operable by said change keys for dispensing the correct change from a dollar tender, means for operating the machine to deliver the correct change for tenders of twenty-five, fifty, or seventy-five cents including said change keys, separate keys and shiftable throw-out mechanisms separate from said separate keys but operated by said separate keys to incapacitate certain of the dispensing mechanisms operated by said change keys on a dollar basis on the operation of said change keys, means for operating the machine to deliver the correct change for tenders in amounts less than one dollar and ending in

five or zero other than the tenders of twenty-five, fifty and seventy-five cents including said change keys, a zero key and a five key and throw-out mechanism separate from said zero

5 key and five key but operated by the same including the throw-out mechanisms of said twenty-five, seventy-five and fifty cent keys to incapacitate all of the dispensing mechanisms operated by said change keys on a dollar basis 10 on the operation of said change keys except those necessary for dispensing the correct change for tenders last above mentioned of less than one dollar, additional means operable by said change keys for effecting the delivery of a nickel, said change keys when used for tenders in amounts less than a dollar and ending in five or zero other than the tenders of twenty-five, fifty and seventy-five cents acting on the coin dispensing mechanisms capable of delivering change of from 20 one to ten cents, and means controlled by any of the operated change keys when furnishing change on less than a dollar basis to move said separate keys and their associated mechanisms to an inoperative position after any single operation of the machine on less than a dollar basis.

7. In a coin changing machine, the combination of a coin tray having compartments for different denominations of coins including a half dollar, twenty-five, nickel and two ten cent compartments from which change can be made on a dollar tender basis, change keys 1 to 99, change key controlled ejector mechanism for each compartment including an ejector finger capable of movement to an inoperative position and selectively operable by said change keys for dispensing the correct change from a dollar tender, a key for a twenty-five or a seventy-five cent tender, a key for a fifty cent tender, shiftable throw-out mechanisms controlled respectively by said last named keys operably engageable with the fingers of the ejector mechanisms for the half dollar and twenty-five cent coins respectively to move these fingers to an inoperative position to incapacitate these ejector mechanisms to furnish change from the half dollar or twenty-five cent compartments when operating one of the change keys 1 to 95 on a tender of twenty-five, fifty, or seventy-five cents, a zero and a five key and shiftable throw-out mechanism controlled by either said zero or five key for effecting the operation of said first named throw-out mechanisms to move the fingers of the ejector mechanisms controlled thereby to an inoperative position and also operatively engageable with the fingers of the ejector mechanisms for the two dime compartments to move their fingers to an inoperative position to incapacitate said ejector mechanisms for making change when operating one of said change keys for any tender of five or multiple thereof or ten or multiple thereof other than twenty-five, seventy-five, or fifty cents, additional means operable by said change keys for effecting the delivery of a nickel, the change keys 1 to 95 when used for tenders in amounts less than a dollar and ending in five or zero other than the tenders of twenty-five, fifty and seventy-five cents acting on those ejector mechanisms capable of delivering change of from one to ten cents.
